Primary Examiner — Joseph Kukella*Assistant Examiner* — Arva P Adams(74) *Attorney, Agent, or Firm* — Kagan Binder, PLLC(57) **CLAIM**

The ornamental design for a kettle, as shown and described.

DESCRIPTION

FIG. 1 is a perspective view of a kettle showing our new design;
FIG. 2 is a front view thereof;
FIG. 3 is a back view thereof;

FIG. 4 is a right side view thereof, the left side view being a mirror image of the right side view;

FIG. 5 is a top view thereof; and,

FIG. 6 is a bottom view thereof.

The broken lines showing the remainder of the kettle according to the present invention are for environmental purposes only and form no part of the claimed design.

1 Claim, 6 Drawing Sheets# US D999,010 S
